(57) **CLAIM**

The ornamental design for a sunglasses clip holder, as shown and described.

DESCRIPTION

FIG. 1 is a front, top and right side perspective view of a sunglasses clip holder, showing my new design;

FIG. 2 is its usage status diagram;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partial enlargement of FIG. 1;

FIG. 10 is a front, top and right-side perspective view of a second embodiment;

FIG. 11 is its usage status diagram;

FIG. 12 is a front view thereof;

FIG. 13 is a rear view thereof;

FIG. 14 is a left side view thereof;

FIG. 15 is a right side view thereof;

FIG. 16 is a top view thereof; and,

FIG. 17 is a bottom view thereof.

The dash-dot-dash broken lines indicate the boundaries of the enlarged detail view, and form no part of the claimed design.
